UNITED STATES PATENT OFFICE.

CHARLES SHLAGEL, OF CLARA CITY, MINNESOTA.

GRINDING DEVICE.

Application filed August 13, 1921. Serial No. 492,049.

To all whom it may concern:

Be it known that I, CHARLES SHLAGEL, a citizen of the United States, and a resident of Clara City, in the county of Chippewa 5 and State of Minnesota, have invented a new and Improved Grinding Device, of which the following is a full, clear, and exact description.

The invention relates to devices for grinding engine cylinders and other similar work, and its object is to provide a new and improved grinding device arranged for convenient attachment to a lathe and more specially designed for grinding the interior surface 10 of a worn-out cylinder of an internal combustion engine to make such cylinder again true and smooth for the proper working of the piston.

Another object is to permit of grinding a cylinder accurately and in a comparatively short time.

Another object is to provide a grinding device which is simple and durable in construction, very effective in operation, and 25 not liable to get easily out of order.

With these and other objects in view the invention consists of certain novel features of construction as hereinafter shown and described and then specifically pointed out 30 in the claims.

A practical embodiment of the invention is represented in the accompanying drawings forming a part of this specification, in which similar characters of reference indicate 35 corresponding parts in all the views.

Figure 1 is a side elevation of the improved grinding device in position on a lathe for grinding a worn-out or untrue cylinder of an internal combustion engine.

Figure 2 is a transverse section of the same on the line 2—2 of Figure 1.

Figure 3 is an enlarged longitudinal central section of the grinding wheel, its arbor, and the mounting therefor.

Figure 4 is a cross-section of the same on the line 4—4 of Figure 3.

Figure 5 is a similar view of the same with the parts in a different position, and

Figure 6 is an elevation of the work 50 holder.

The improved grinding device is shown attached to a lathe of usual construction having a bed 10 on which is mounted to travel a carriage 11 fed forward or backward by 55 the usual feed screw 12. On the tail end

of the bed 10 is mounted a work holder 15 provided with a vertically disposed guideway 16 fixed to the bed 10 and on the said guideway 16 is mounted to slide up and down a slide 17 supporting a sidewise adjustable sliding plate or holder 18, on which is removably fastened the work 19 by the use of bolts 20 or other fastening means. As shown in Figure 1, the work 19 is in the form of a four cylinder block, of which the 60 uppermost cylinder is to be ground at the time. In order to impart a transverse sliding movement to the sliding plate 18, use is made of a transversely extending screw rod 21 journaled in the slide 17 and screwing in 65 a nut 22 attached to or forming part of the sliding plate 18. The forward end 23 of the screw rod 21 is made polygonal for the application of a handle 24 to allow the attendant of the machine to conveniently turn the 70 screw rod 21 with a view to move the sliding plate transversely on the slide 17. In order to move the sliding plate and with it the slide 17 up or down, use is made of a vertically disposed screw rod 25 screwing in 75 a nut 26 attached to or forming part of the guideway 16. On the upper end of the screw rod 25 is secured a bevelled gear wheel 27 in mesh with the bevelled gear wheel 28 attached to the rear end of a transversely extending shaft 29 mounted to turn in the 80 slide 17. The outer polygonal end 30 of the shaft 29 is adapted to receive the handle 24 to permit the attendant to turn the shaft 29 with a view to raise or lower the sliding 85 plate 18. By the arrangement described the work 19 can be readily adjusted to move the cylinder to be ground into accurate position for grinding as hereinafter more fully explained. 90

In order to grind the interior surface of the cylinder, use is made of a grinding wheel 40 secured on the right hand end of a longitudinally extending arbor 41 journaled in suitable bearings 42 arranged within an arbor supporting tube 43 extending divergently through a hollow shaft 44 mounted to turn in suitable bearings arranged in standards 45 attached to the top of the carriage 11. The left hand end of the arbor 41 is provided with a pulley 50 connected by a belt 51 with a pulley 52 secured on a sleeve 53 journaled in suitable bearings 54 arranged on the upper ends of the standards 45. Through the sleeve 53 extends a driv- 100 105 110

ing shaft 55 connected by key and keyway 56, 57, with the sleeve 53 to rotate the latter and to allow the sleeve to slide lengthwise on the driving shaft 55. The driving shaft 5 55 is journaled in bearings 60 attached to the head stock 61 of the lathe and the said driving shaft 55 is provided with a pulley 62 connected by a belt 63 with one of the cones of the cone pulley 64 mounted on the 10 lathe. The cone pulley 64 is connected by a belt 65 with other machinery for imparting a rotary motion to the cone pulley 64; which by the belt 63 and the pulley 62 rotates the driving shaft 55. The rotary motion of the 15 driving shaft 55 is transmitted by the sleeve 53, pulleys 52, 50, and the belt 51 to the arbor 41 to rotate the latter and its grinding wheel 40. It will be noticed that on moving the carriage 11 forward or backward, the sleeve 53 slides on the driving shaft 55 without disconnecting one from the other, and hence, the sleeve 53 is rotated whenever the driving shaft 55 is rotated.

In order to impart a planetary movement 25 to the grinding wheel 40 for the latter to grind the inner surface of the engine cylinder, the following arrangement is made:— On the hollow shaft 44 is secured a bevelled gear wheel 70 in mesh with a bevelled pinion 30 71 secured on the lower end of a shaft 72 journaled in a bearing 73 attached to or forming part of one of the standards 45. On the upper end of the shaft 72 is secured a worm wheel 75 in mesh with a worm 35 76 attached to the sleeve 53 to rotate with the same. Thus the rotary motion of the sleeve 53 is transmitted by the gearing thus described to the hollow shaft 44. Against the left hand end of the hollow shaft 44 bears 40 the conical face 80 of a collar 81 screwed or otherwise secured to the left hand end of the arbor supporting tube 43. On the right hand end of the hollow shaft 44 is screwed or otherwise secured, a collar 82 in which is 45 mounted the eccentric hub 83 of a worm wheel 84 secured to the arbor supporting tube 43. The worm wheel 84 is in mesh with a worm 85 secured or formed on a worm shaft 86 journaled in suitable bearings 87 50 attached to or forming part of the collar 82. A handle or other suitable tool is applied to the outer polygonal end 88 of the worm shaft 86 to permit the attendant of the machine to rotate the worm wheel 84 with a view to 55 vary the angularity of the axis of the arbor 41 with that of the hollow shaft 44, it being understood that the axis of the hollow shaft 44 coincides with the axis of the cylinder to be ground by the wheel 40. It is understood 60 that the collar 81 forms a pivotal connection between the left hand end of the arbor supporting tube 43 with the hollow shaft 44, and the worm wheel 84 on account of being eccentrically attached to the tube 43 and being eccentrically mounted in the collar 82.

provides the desired divergence of the axis of the arbor 41 relative to that of the hollow shaft 44.

The operation is as follows:—When the several parts are in the position, as shown in Figure 1, and the lathe is running, then the carriage 11 is fed from the left to the right by the feed screw 12 to move the grinding wheel 40 into the uppermost cylinder of the work 19 held on the sliding plate 18. A continuous rotary motion is given to the arbor 41 and its grinding wheel 40, as previously explained, and a bodily planetary motion is given to the grinding wheel 40, as above set forth, to cause the peripheral face 80 of the grinding wheel 40 to move circularly in contact with the inner surface of the cylinder to be ground. As the axis of the rotating hollow shaft 44 coincides with the axis of the cylinder, it is evident that the inner surface of the cylinder is accurately ground by the grinding wheel 40 and the latter is bodily advanced by the movement of the carriage 11 to grind the cylinder throughout its depth. By adjusting the angular movement of the arbor 41 relative to the hollow shaft 44 on turning the worm shaft 86, as previously explained, the desired amount of throw is given to the grinding wheel 40 to cause the latter to make a cut to the required depth. The grinding device shown and described can be readily attached to a lathe of usual construction. It will also be noticed that a worn-out or untrue cylinder can be accurately ground by the use of the grinding device to render such cylinder true and smooth for proper working of the piston.

Having thus described my invention, what I claim as new and desire to secure by Letters Patent is:

1. A grinding attachment for lathes comprising a support arranged for attachment to a lathe carriage, a work holder arranged for attachment to the tail end of a lathe and adapted to support a cylinder to be ground, an arbor carrying a grinding wheel adapted to grind the interior surface of the cylinder, an arbor supporting tube in which the arbor is journaled, a hollow shaft journaled in the said support and within which the said arbor supporting tube is divergently mounted, a driving shaft adapted to be driven from the lathe arbor, a sleeve mounted to slide on and to turn with the said driving shaft, the said sleeve being journaled in the said support, fast speed driving means connecting the said sleeve with the said arbor to rotate the latter at a high speed, and slow speed driving means connecting the said sleeve with the said hollow shaft to rotate the latter at a slow speed.

2. A grinding attachment for lathes comprising a support arranged for attachment to a lathe carriage, a work holder arranged for attachment to the tail end of a lathe and

- adapted to support a cylinder to be ground, an arbor carrying a grinding wheel adapted to grind the interior surface of the cylinder, an arbor supporting tube in which the arbor 5 is journaled, a hollow shaft journaled in the said support and within which the said arbor supporting tube is divergently mounted, driving means for rotating the said arbor, driving means for rotating the said hollow 10 shaft, a worm shaft having a worm and journaled transversely in one end of the said hollow shaft, a worm wheel secured eccentrically on the said arbor supporting tube and in mesh with the said worm, the said 15 worm wheel being eccentrically mounted on the said hollow shaft, and a pivotal connection between the other end of the said hollow shaft and the said arbor supporting tube.
- 20 3. In a grinding device, a driven arbor carrying a grinding wheel at one end, a tube in which the arbor is journaled, a driven hollow shaft through which extends the said tube, the latter being mounted to swing at 25 one end on one end of the said hollow shaft, an eccentric held eccentrically on the other end of the said shaft and eccentrically supporting the said tube, and manually controlled means mounted on the said shaft and 30 engaging the said eccentric to turn the latter to vary the angularity of the said tube and arbor relative to the shaft.
4. In a grinding attachment for lathes, comprising a support adapted to be attached to a lathe carriage, a hollow shaft 35 mounted in the support and provided with a collar at one end, an arbor supporting tube in the hollow shaft and provided with a collar having a conical face with which one end 40 of the hollow shaft engages, a worm wheel having an eccentric hub extending into the collar of the hollow shaft, a worm shaft mounted on said collar and meshing with the worm wheel, an arbor mounted in the said tube and carrying a grinding wheel at one end, means for rotating the arbor, and means for rotating the hollow shaft.
5. In a grinding attachment for lathes, comprising a support adapted to be secured to the lathe carriage, a hollow shaft mounted 50 in the support, a tube pivoted at one end in the hollow shaft, an eccentric on the tube and upon which one end of the hollow shaft turns, an arbor mounted in the tube and carrying a grinding wheel at one end, a sleeve mounted in the support, a driven shaft extending through the sleeve and upon which the sleeve slides but turns therewith, gearing between the sleeve and the arbor, and gearing between said sleeve and the hollow shaft.
6. In a grinding attachment for lathes, comprising a support adapted to be secured to the lathe carriage, a hollow shaft mounted 55 in the support, a tube pivoted at one end in the hollow shaft, an eccentric on the tube and upon which one end of the hollow shaft turns, an arbor mounted in the tube with its ends projecting beyond the ends of the tube, a grinding wheel on one end of the arbor, a pulley on the other end of the arbor, a driven shaft, a sleeve mounted to slide on the shaft and to turn therewith, a pulley on the sleeve, a belt connecting the pulley with the pulley of the arbor, a bevel gear wheel 60 on the hollow shaft, a shaft having at one end a bevel pinion meshing with the bevel gear wheel and a worm wheel at its other end, and a worm on the sleeve meshing with said worm wheel.

CHARLES SHLAGEL.
